UNITED STATES PATENT OFFICE.

ALBERT J. SCHWALGE, OF CHICAGO, ILLINOIS.

SWIMMING APPLIANCE.

Application filed July 11, 1927. Serial No. 204,831.

My invention relates to swimming appliances, and more particularly to such devices as are worn on the feet of the swimmer to facilitate propulsion, and it is my 5 main object to provide a device of this kind which is highly efficient in operation.

A further object of my invention is to so design the novel swimming appliance that it presents a broad resistance to the water 10 during the swimming stroke and practically no resistance during the return stroke.

A still further object of the invention is to construct the same with a generally flat base, so that it may be used with comfort on 15 the ground when approaching or leaving the body of water.

Another object of my invention is to construct the same with a peculiar loose formation, so that warping or distorting strains 20 upon the same will not be induced by the weight of the wearer or the stress of walking movements.

A final but nevertheless important object 25 of my invention is to construct the novel appliance of very light material and with protected edges, so that the wearer will not experience discomfort in any way while walking or swimming.

With the above objects in view and any 30 others that may suggest themselves in the specification and claims to follow, a better understanding of the invention may be gained by reference to the accompanying drawing, in which—

35 Figure 1 is a plan view of the appliance as worn on the foot, the latter being denoted by dotted lines;

Fig. 2 is a side view, showing the manner 40 in which the appliance is positioned when the foot takes the rearward or active stroke;

Fig. 3 is a similar view, denoting the position of the appliance when the foot takes 45 the forward or idle stroke;

Fig. 4 is a front view, the showing of the 50 foot not being included; and

Figs. 5 and 6 are detail sections, taken on lines 5—5 and 6—6 of Figure 2, respectively.

I am familiar with the fact that swimming appliances of various designs have 55 been patented and probably marketed, including devices worn on the swimmer's feet; but I have found that all such devices have either been too heavy or clumsy, did not materially improve the swimming operation, or 60 were too intricate to be worn with comfort or manufactured at a reasonable figure.

The present appliance is intended to overcome these deficiencies, and to fulfill the objects contemplated above.

To point out the construction of my invention by specific reference to the drawing, 60 5 denotes the paddle section of the device, which applies over the foot, and 6 the sole section, which applies under the same. The paddle section is generally of elliptical 65 design and transversely arched to more nearly conform to the shape of the foot; also, it is inclined similarly to the foot and extends a short distance beyond the same. The sole section has the form of the standard shoe 70 sole, and is only of the necessary size to fit the base of the foot. At the rear, both sections are joined by a strap 7 to encircle the instep, and also a strap 8 extended from the strap 7 to encircle the ankle. These straps 75 necessarily carry buckles for securing purposes after they have encircled the foot, so that the appliance is securely carried at the rear portion of the foot. Near the frontal 80 portion the sole section 6 carries an arched cross strap 9 having the form of a closed loop, which serves to receive the frontal part of the instep to facilitate a hold on the frontal part of the sole section.

At the region of the toes, the two sections 85 are connected near their side edges by wire links 10 which are made with heads or loops 11 after they are passed through perforations 12 in the respective sections these links 90 permitting free relative motion of the respective sections to a limited degree. A similar link 10^a is provided intermediately of the links 10, at a position corresponding to the space between the great toe and the remaining toes. The lower end of the link 95 10^a, however, is not connected to the sole section proper, but to an up-struck tongue 13 thereof, the relation here also being loose as in the previous instance. The tongue is 100 directed longitudinally of the appliance, and is intended to occupy the space between the great toe and the balance of the toes with the primary object of forming a smooth contact for the adjoining toes while providing for an intermediate link (10^a) at the same 105 time. In other words, the possible discomfort due to this link is avoided by the use of the tongue 12.

As noted more particularly in Figures 4 and 6, the edge of the sole section 6 is pressed 110 with a channel 6^a; also the edge of the paddle section 5 is formed with a slight inward

curve, denoted at 5^a. The sections 5 and 6 are made of thin sheet aluminum primarily for extreme lightness and for facility in forming the characteristics 5^a and 6^a just described. When the device is used for the active or rearward or swimming stroke, as indicated in Figure 2, it will be seen that the portions 5^a and 6^a will facilitate the pocketing action of the sections upon the water, so as to present a greater resistance thereto and aid the foot in the propulsion of the swimmer. Since the paddle section 5^a is considerably larger than the sole section 6^a, the active stroke of the swimmer will present a formidable resistance to the water. In order to augment the force of the paddle section, especially at its inner edge, where the water is apt to flow through upon the swimmer's ankle, I have rounded the edges adjacent to the ankle to form channels 5^b, more clearly shown in the detail of Fig. 5, these also acting as pockets to prevent the rush of water upon the ankle and therefore increase the efficiency of the paddle section.

It will be seen that, by forming the sole section 6 with the marginal channel 6^a, that the same remains flat generally, so that it acts as an ordinary sole when the swimmer walks upon the beach or landing adjacent to the body of water. The channel feature is entirely above the level of the sole bottom, so that it does not cut the ground or into the soil or sand, and is therefore not subject to be warped, distorted or broken. This feature is of importance when the weight of the wearer and the lightness of the metal are considered, and it is my intention that the weight be fully carried by the general portion of the sole section which is in full contact with the surface upon which the swimmer walks while approaching or leaving the body of water. Also, the channel acts as a rim to seat the foot and prevent its shifting. Referring to the links 10 and 10^a my object in having these is not only to form a tie between the frontal portions of the paddle and sole sections, but also to provide for the relative motion of these sections with each step taken by the wearer. Conversely, if the sections were rigidly connected while of such thin metal as described, it may be imagined that each step of the wearer would induce a strain which would soon result in distortion or a rupture. Consequently, the presence of the links 10 and 10^a permits the paddle section to move forward or backward as the wearer takes a forward step and to return as his foot lands on the ground, so that the appliance is not subjected to any hardship or unnatural stresses. Also, the loose connection of the links permits the paddle section to maintain its resisting position in spite of possible variations in the angle of the sole section during the swimming action.

It will be seen that I have provided a device of extreme simplicity, lightness, and durability for the purpose intended. No extra attachments or device will be required for the application of the straps 7 and 8; the paddle section is simply formed with a rolled hook 14 to receive an adjusting loop of the strap 8 and the sole section 6 is slotted at 15 to permit the strap 7 to be passed through it. All considered, the appliance forms a material aid to the swimmer in displacing as much water as possible with his feet, consistent with simplicity and lightness in the make-up of the appliance. It will be understood that, wherever advisable, the marginal edges of the sections will be doubled back, as indicated at 17, to prevent the feet from being cut or otherwise injured.

I claim:

1. A pedal swimming appliance comprising a paddle section over the foot extending from forwardly of the toes to the ankle and generally conforming thereto, said section being channeled adjacent the ankle portion, and means connecting the said paddle section to the ankle and foot.

2. A pedal swimming appliance comprising a paddle section over the foot and generally conforming thereto, a sole section secured under the foot, and means connecting the paddle section with the sole section, said paddle section being extended forwardly and laterally beyond the sole section and formed with a downturned marginal rim.

3. A pedal swimming appliance comprising a paddle section over the foot and generally conforming thereto, a sole section secured under the foot, and means connecting the paddle section with the sole section, said paddle section being formed with rearwardly converging side edges, and such edges being turned to constitute pockets.

4. A pedal swimming appliance comprising a paddle section over the foot and generally conforming thereto, a sole section secured under the foot, and means connecting the paddle section with the sole section, said sole section being formed with a marginal upstanding rim continuous from adjacent the instep about the entire forward portion of the sole.

5. A pedal swimming appliance comprising a paddle section over the foot and generally conforming thereto, a sole section secured under the foot, and means connecting the paddle section with the sole section, said sole section being formed with a marginal upstanding rim, and the latter presenting a recess on the under side.

6. A pedal swimming appliance comprising a paddle section over the foot and generally conforming thereto, a sole section secured under the foot, and means connecting the paddle section with the sole section, said

sole section being formed with a marginal upstanding rim, and the latter presenting a channel on the under side.

7. A pedal swimming appliance comprising a paddle section over the foot and generally conforming thereto, a sole section secured under the foot, and means for loosely connecting the paddle section with the sole section, said sole section having a marginal upstanding ridge surrounding the foot and a channel on the underside formed thereby.

8. A pedal swimming appliance comprising a paddle section over the foot and generally conforming thereto, a sole section secured under the foot, links connecting the paddle section with the toe section at the sides, a link depending from the paddle section intermediately, and a longitudinally-directed tongue projected from the sole section to connect with such link. 15

In testimony whereof I affix my signature. 20

ALBERT J. SCHWALGE.
